UNITED STATES PATENT OFFICE.

CHESTER LICHTENBERG, OF SCHENECTADY, NEW YORK, ASSIGNOR TO GENERAL ELECTRIC COMPANY, A CORPORATION OF NEW YORK.

CIRCUIT-INTERRUPTER.

1,137,340.

Specification of Letters Patent. Patented Apr. 27, 1915.

Application filed October 11, 1912. Serial No. 725,176.

To all whom it may concern:

Be it known that I, CHESTER LICHTENBERG, a citizen of the United States, residing at Schenectady, county of Schenectady, State of New York, have invented certain new and useful Improvements in Circuit-Interrupters, of which the following is a specification.

My invention relates to devices for interrupting electric circuits, and more particularly to oil circuit interrupters of the type in which there is an air space of greater or less volume above the surface of the oil.

I have found that in an oil circuit interrupter having an air space above the oil, the air in the air space mixes with oil vapor and forms an inflammable mixture. Under certain conditions the proportion of air and oil vapor may be such that the mixture is explosive. I have, furthermore, found that much of the destructive effects sometimes observed when oil circuit interrupters of this type are opened under extremely severe conditions, are due to the ignition of this mixture of oil vapor and air at the surface of the oil, rather than to any direct explosive action of the arc. In many cases the circuit has been opened and the arc practically extinguished before the destructive explosion and rush of fire from the circuit interrupter occurs.

The object of my invention is to prevent ignition of the inflammable mixture in the air space above the oil.

To this end I provide some suitable means which will permit the vapors generated by the arc in the body of the oil to escape freely from the oil, but which will insure that none of the hot vapors or heated particles given off by the arc can reach the air space above the arc until they are cooled so much that they cannot ignite an explosive or inflammable mixture in the air space.

For a better understanding of my invention, reference may be had to the accompanying drawing, in which, merely for purposes of illustration, I have shown one of the various forms in which my invention may be embodied, and in which—

Figure 1 is a longitudinal section of one form of circuit interrupter embodying my

invention; Fig. 2 is a transverse section of the circuit interrupter shown in Fig. 1; Fig. 3 is a longitudinal section of a circuit interrupter in which my invention is embodied in a slightly modified form; and Fig. 4 is a horizontal section along the line 4—4 of Fig. 3 showing details of construction.

In the particular form of circuit interrupter which I have chosen to illustrate my invention, an oil tank 1 is a partially filled with oil or other suitable insulating fluid.

My invention is applicable to any circuit interrupter having an insulating fluid which, under the influence of the arc or in any other way, will produce an inflammable or explosive mixture in the air space above the insulating fluid but oil is the insulating fluid most commonly used in circuit interrupters of this type. The oil tank 1 is provided with a cover 2 which fits the oil tank quite closely and leaves between the cover and the surface of the oil an air space which may be of greater or less volume, depending upon the size of the circuit interrupter. The cover 2 supports insulators 3 on the lower ends of which are mounted fixed contacts 4 submerged in the oil in the oil tank. When the circuit is to be closed, the fixed contacts 4 are connected by a bridging contact 5 mounted upon the lower end of a vertically movable operating rod 6, which may be raised and lowered by some suitable actuating mechanism, not shown. When the circuit is to be opened, the bridging contact 5 drops away from the stationary contacts 4 into the position shown in Fig. 1. As the contacts separate, arcs are formed which produce a very high temperature and result in the formation of very hot bubbles of oil vapors and glowing particles of metal. These arcs are eventually extinguished by the oil.

In order to guard against ignition of any inflammable or explosive mixture in the air space above the oil, I mount a suitable barrier or screen above the point of separation of the contacts and between the contacts and the surface of the oil, so that hot gases and particles cannot reach the air space above the oil except by passing through the barrier or screen. This barrier or screen may be

made in many different forms as long as it is so constructed that hot gases and particles passing through it must be cooled to the desired extent before they can escape into the 5 air space above the oil. The preferred form of barrier, as shown in the drawing, is made in the form of a grid consisting of a plurality of plates 7, mounted side by side and insulated from one another, these plates being 10 strung along on suitable supports 8 which extend across the oil tank and are supported in any suitable way, as by the walls of the oil tank. The plates 7 are made of some good heat conducting material, preferably 15 metal. The spacing of the plates with relation to one another is such that gases can pass from the neighborhood of the arc through the barrier and into the air space above the oil, but will necessarily be in such 20 intimate contact with the plates while passing between them that the gases are cooled to a temperature considerably below that required to ignite any inflammable or explosive mixture which may be present in any oil 25 space above the oil.

The grid or barrier may be located in any position which will enable it to intercept all the hot gases before they pass into the air space above the oil, but in the preferred construction it is located just below the surface 30 of the oil, as shown in the drawing. By this construction, the plates 7 are always submerged in the oil, remain at the temperature of the oil, and offer considerable resistance 35 to a sudden upward rush of gases, owing to the viscosity of the oil and the adhesion of the oil to the plates. There is no danger that the barrier, even when constructed of metal plates, will act as a bridge to permit 40 the arc to extend from one fixed contact to the other. The plates 7 are insulated, and such an arc could not exist, as it would be divided up into a large number of short arcs in series, exposed both to the cooling action 45 of the plates 7 and also to the extinguishing action of the oil.

In the particular arrangement shown in Fig. 1, the plates 7 with their upper edges at the same level, are disposed transversely 50 of the oil tank. The plates adjacent to the insulators 3 are the narrowest, the others gradually increasing in width toward the operating rod 6 and toward the sides of the oil tank. As a result of this construction, 55 the lower edges of the plates form a sort of bell or inverted funnel which catches all the arc gases and compels them to pass through the plates on their way to the air space above the oil.

60 In the modification shown in Figs. 3 and 4, the barrier or grid is made up of a number of concentric heat conducting plates 9 mounted around each insulator and held in place by suitable supports 10. The plates 65 operate in the same way as the plates 7 and

are so mounted that their lower edges form a bell or inverted funnel for catching all of the oil bubbles and particles which are given off by the arc and which tend to rise through the oil into the air space above the oil.

70

As in the arrangement shown in Fig. 1, the plates 9 are so spaced that the gases can pass between them with comparatively little resistance, but nevertheless are so cooled during their passage that there is no danger 75 of ignition of inflammable or explosive mixtures in the air space above the oil.

What I claim as new and desire to secure by Letters Patent of the United States, is,

1. A circuit interrupter comprising a vessel containing insulating liquid, a cooling barrier mounted just below and near the surface of said liquid having a plurality of permanently opened constricted passages for the escape of gases from said liquid, and 80 relatively movable coöperating contacts submerged in the liquid in said vessel and separable to draw an arc beneath said cooling barrier.

2. A circuit interrupter comprising a vessel partially filled with oil, relatively movable coöperating contacts separable in said vessel beneath the surface of the oil, and cooling means mounted just below and near the surface of the oil for cooling the products of 95 the arc before said products reach the surface of the oil.

3. A circuit interrupter comprising a vessel partially filled with oil, relatively movable contacts mounted to separate in said 100 vessel beneath the surface of the oil, and a plurality of cooling members spaced apart and mounted just below and near the surface of the oil for reducing the temperature of the arc gases before they reach the air space 105 above the oil.

4. A circuit interrupter comprising a vessel containing insulating liquid, relatively movable coöperating contacts separable to draw an arc in said liquid, and a metal cooling screen comprising a plurality of plates 110 so mounted just below and near the surface of the oil as to form for the hot arc gases submerged vents which cool to a safe temperature the gases passing through it.

115

5. A circuit interrupter comprising a vessel partially filled with oil, relatively movable contacts mounted to separate in said vessel beneath the surface of the oil, and a cooling grid mounted just below and near the surface of the oil comprising a plurality of permanently opened constricted passages interposed in the path of hot gases to cool 120 said gases before they reach the air space above the oil.

125

6. A circuit interrupter comprising a vessel containing insulating liquid, relatively movable coöperating contacts separable to draw an arc in said liquid, and a plurality 130 of plates concentrically arranged just below

and near the surface of the liquid to form a cooling screen between the arc and the surface of said liquid.

7. A circuit interrupter comprising a vessel partially filled with oil, relatively movable contacts mounted to separate in said vessel beneath the surface of the oil, and a plurality of plates insulated from one another and concentrically arranged just below

and near the surface of the oil to form a screen through which gases generated by the arc must pass to reach the surface of the oil.

In witness whereof, I have hereunto set my hand this 7th day of September 1912.

CHESTER LICHTENBERG.
